Primary Examiner — Barbara Fox*Assistant Examiner* — Kristin E Reed(74) *Attorney, Agent, or Firm* — Leydig, Voit & Mayer, Ltd.(57) **CLAIM**

The ornamental design for a rail mount for a table top, as shown and described.

DESCRIPTION

This application is related to U.S. Design Patent application Ser. No. 29/602,869, filed May 4, 2017, entitled "Arm Bracket For Table Mount," and U.S. Design Patent application Ser. No. 29/602,871, filed May 4, 2017, entitled "Mounting Bracket," the entire disclosures of which are incorporated herein by reference.

FIG. 1 is a front, right side and top perspective view of a rail mount for a table top showing my new design;

FIG. 2 is a left side view thereof;

FIG. 3 is a right side view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the figures depict portions of a rail mount for a table top that form no part of the claimed design.

1 Claim, 4 Drawing Sheets(56)
